CLAIM

We claim, the ornamental design for catheter, as shown and described.

DESCRIPTION

FIG. 1 is a front view of a catheter, showing our new design;

FIG. 2 is a rear view thereof;

FIG. 3 is a top plan view thereof;

FIG. 4 is a bottom plan view thereof;

FIG. 5 is a left side view thereof; and,

FIG. 6 is a right side view thereof; and,

FIG. 7 is a reference reduced-scale front view showing the catheter in a wound condition.

The broken lines shown in the drawings represent portions of the catheter that form no part of the claimed design. The break lines indicate that the appearance of any portion of the catheter between the break lines form no part of the claimed design.

1 Claim, 5 Drawing Sheets
